METHOD OF COPPER SWEETENING

Harold E. Messmore, Bartlesville, Okla., and
James M. Mason, Chicago, Ill., assignors to
Phillips Petroleum Company, a corporation of
Delaware

Application September 10, 1943, Serial No. 501,876

3 Claims. (Cl. 196—30)

This invention relates to the sweetening of gasoline and other petroleum oils, and more particularly it relates to an improved process of carrying out a sweetening operation. Specifically, the invention relates to improvements in the sweetening of petroleum oils by the cupric chloride method shown in Schulze et al., U. S. 1,964,-219, and in Henry et al., U. S. 2,089,373.

In the sweetening of sour petroleum distillates by the so-called liquid copper sweetening process, the sour oil containing sulfur in the form of mal-odorous mercaptans is intimately and vigorously contacted with an aqueous solution of a cupric salt, usually cupric chloride (and may be made from cupric sulfate and a soluble chloride, as sodium chloride). The mixture of the copper chloride treating solution and the oil is then allowed to settle and separate, whereupon the sweetened upper oil layer is removed from the lower aqueous layer. Usually the sweetened gasoline is next contacted with a stabilizing agent such as an alkaline sodium sulfide solution which treatment serves to remove any traces of copper compounds and prevents color instability or other deterioration of the product. The copper sweetening agent is regenerated by blowing with a free oxygen-containing gas such as air, then recirculated for further use.

Certain extraordinary gasolines or petroleum distillates are slow to sweeten by the conventional copper sweetening method described above. This is believed to be due largely to the concentration and type of mercaptan contained in these oils. Since mercaptans may be termed thioalcohols, there may then be the same types of mercaptans as alcohols, for example, primary, secondary and tertiary, depending on the number of replaceable hydrogen atoms remaining attached to the carbon atom to which the mercaptan (—SH) group is attached. It is known that primary mercaptans may be rapidly converted to the corresponding disulfides by the oxidizing action of cupric chloride, secondary mercaptans less rapidly, and tertiary mercaptans relatively slowly, and it is thought that the tertiary mercaptan content may be the cause for the relatively slow sweetening of some gasolines and petroleum distillates.

Since hydrocarbon oils and aqueous solutions, such as the copper chloride sweetening solution, are immiscible, it is necessary to obtain intimate contact therebetween in an attempt to expedite reaction. At the same time, too vigorous contacting may result in the formation of a relatively stable emulsion. It has been found that mixing of these two immiscible liquids by a centrifugal

mixing pump gives sufficient contacting in the normal commercial installation. Obviously, the time of contact in such a mixing device is of limited duration.

In the treatment of oils which are abnormally slow to sweeten, it has been suggested to use a "bypass" for recirculation of a portion of the mixing pump discharge (intimate mixture of copper chloride solution and oil) into the sour oil charge line. This recirculation increases the apparent time of contacting of the sour oil and the aqueous sweetening agent. At the same time the partially spent treating solution can react with some easily convertible mercaptans in the sour oil so that at the inlet to the mixing pump the oil is actually partially sweetened. Another improvement has been to install a "packed tower" type contactor so that the above mentioned bypassed mixture of partially spent copper treating solution and sweetened oil and sour charge oil may be more intimately mixed by the time the mixture reaches the mixing pump. In this method of operation the new or fully regenerated copper treating solution is added to this latter mixture just previous to entrance into the mixing pump.

We have now further improved this method of sweetening by removing substantially all of the fully spent treating solution prior to the addition of the regenerated solution. In this improved operation, to the partially spent treating solution is added the raw, sour gasoline or petroleum distillate to be sweetened, wherein the easily oxidized mercaptans are converted into the corresponding disulfides. After this partial sweetening takes place the resulting spent solution is removed from the partially sweetened oil. Then fully regenerated treating solution is added wherein this solution of high oxidizing power may react with the mercaptans which are slower and more difficult to sweeten. This improved process permits the more efficient use of the copper chloride treating solution for the sweetening of oils generally considered difficult or slow to sweeten.

The oxidizing or sweetening power of the copper chloride solution may be measured by conventional potentiometric methods using a saturated calomel electrode. In commercial practice a fully aerated and regenerated copper treating solution may have an oxidation potential as high as 410-420 millivolts, abbreviated hereinafter m. v. A spent solution of the same copper and chloride content may have an oxidation potential as low as 360 m. v. or at times even lower. If one volume of spent treating solution of 360 m. v. is mixed with one volume of regenerated solution of 420

m. v., the resulting mixture will possess an oxidation potential of approximately 380 m. v., and not the arithmetic average.

An object of this invention is to improve the copper chloride solution sweetening process.

Another object of this invention is to improve the copper chloride solution sweetening process in such a manner that oil stocks generally considered difficult to sweeten may be more easily and rapidly sweetened.

Still another object of this invention is to improve the operation of the liquid copper chloride sweetening process wherein the treating solution of low oxidizing power may sweeten the sourness which is easy to sweeten and the fully regenerated treating solution of high oxidizing power may react with the sourness which is normally considered difficult to sweeten.

Still other objects and advantages of our improved process will be apparent to those skilled in the art from a careful study of the following detailed disclosure, in which the figure illustrates diagrammatically one form of apparatus of the present invention by which our improved process may be carried out.

Referring now to the accompanying drawing, a motor driven centrifugal mixing pump is indicated at 1 and a separating tank at 2, in which gravity separation of the treated oil and copper solution takes place. Sour oil to be sweetened enters the system by way of a line 3, controlled by a valve 4. Partially spent copper treating solution enters line 3 from line 13, and the mixture of the sour oil with this copper solution passes downward through the packed contactor tube 6. From this contactor this mixture now containing partially sweetened oil and spent treating solution passes by way of line 7 into the separating tank 8, which is similar in construction to the separating tank 2. From tank 8 the upper partially sweetened oil layer leaves by way of line 9, controlled by valve 10, new or fully regenerated copper treating solution enters by line 11 controlled by valve 12, and the mixture then is taken into the suction side 15 of the centrifugal mixing pump 1. In this mixer these two immiscible liquids are thoroughly and efficiently contacted and an emulsion-like looking mixture is discharged into the separating tank 2 by way of line 16 controlled by valve 17. In this tank sweetened oil and partially spent treating solution separate as two liquid phases, the oil phase passing from the tank by line 18 controlled by valve 19; while the treating solution flows from the tank by line 13, the flow being controlled by valve 20. As mentioned hereinabove, the partially spent treating solution from tank 2 passes through line 13 into line 3, thereby completing the flow cycle of the copper chloride solution.

A bypass line 21 connects the mixing pump discharge line 16 with the sour oil line 3, and the liquid flow therethrough is controlled by valve 22.

Fully spent copper treating solution separated from the partially sweetened oil in separating tank 8, is removed therefrom by line 23 controlled by valve 24. Line 23 conducts this spent solution to an aeration apparatus, not shown, wherein the spent solution is oxidized or regenerated by atmospheric oxygen. The regenerated solution then re-enters the system through line 11.

The packing material 5 in contactor 6 may be essentially any standard material suitable for the purpose at hand. It must, obviously, be inert

toward both the oil being treated and the copper chloride treating solution, the latter being slightly acid. The packing material may be arranged in the contactor 6 in essentially any manner desirable to accomplish the result of breaking up streamlined flow of the two immiscible liquids and promoting contacting and therefore chemical reaction between them. The diameter and length of the contactor 6 are such as to permit appreciable time contacting so that a large part of the mercaptans easy to react may be converted by the time the oil leaves the contactor.

Separating tanks 2 and 8 are equipped with gauge glasses 25 and 26, respectively, of conventional design, for the purpose of observing the position of the interface between the copper solution and oil layers, represented by numeral 27 in separating tank 8 and numeral 28 in separating tank 2.

In the operation of the sweetening process according to our invention, sour oil to be sweetened enters the system through line 3, the flow being controlled by valve 4. Partially spent copper chloride treating solution from line 13 enters line 3 near the latter's junction with the contactor column 6. In this contactor column the said copper chloride solution is rather intimately mixed with the sour oil whereby a certain amount of chemical reaction or sweetening occurs. In this sweetening column, we believe that the major portion of the primary mercaptans, mentioned hereinbefore, a much smaller proportion of the secondary mercaptans, and possibly a very small amount of the slow-to-react tertiary mercaptans are sweetened. Since the primary mercaptans are ordinarily present in oils in far greater proportions than all other types of mercaptans combined, we then believe that a relatively large proportion of the total sweetening actually occurs in this contacting column. The resulting copper treating solution is ordinarily fully spent, especially when treating oils of appreciable sourness.

The mixture of spent treating solution and partially sweetened oil passes from contactor 6 through line 7 into the separating tank 8, wherein the two immiscible liquid phases separate. In this separating tank a high copper solution level as indicated by numeral 27 is carried, the relative amount of treating solution in the tank being much greater than the volume of the partially sweetened oil. It is not necessary to maintain any exact or definite level, since all that is necessary is to make certain that the copper solution remains in this separating tank 8 sufficiently long that substantially all oil has ample time in which to become separated therefrom. Any oil which is withdrawn with the spent treating solution through line 23 will be lost by evaporation during regeneration, unless provision is made for reclaiming same.

By maintaining a high copper solution level in the separating tank 8, the copper solution residence time is considerably longer than is the residence time of the partially sweetened oil therein. It is not necessary that all traces of copper solution be separated from this partially sweetened oil since the regenerated treating solution is added to this partially sweetened oil while the latter is in transit in line 9. The minute amount of spent copper solution has substantially no detrimental effect upon the relatively large amount of regenerated solution added.

The partially sweetened oil and regenerated copper treating solution from line 9 enter the

mixing pump 1, and become thoroughly and vigorously mixed wherein it is intended that the remaining, slower to sweeten mercaptans, become fully sweetened. The oil-solution mixture upon discharge from the mixing pump 1 has an appearance of a coarse grained emulsion, the oil apparently being the continuous phase and the copper treating solution the discontinuous phase. This mixture then passes through line 16 into the separating tank 2 wherein copper solution and sweetened oil separate. In this tank a very low copper solution level is maintained in order to increase to a maximum the retention or settling time of the sweetened oil so that the oil leaving said tank by line 18 will carry no traces of suspended copper treating solution. The settled copper solution may or may not contain traces of oil on account of its relatively short retention time in separator 2. Since this partially spent treating solution is recycled through line 13 to line 3 where sour oil is contacted, it is immaterial whether or not this solution carries oil, and in case it does, we have found it to be very small in amount.

The completely sweetened oil leaving separating tank 2 through line 18 may pass directly to storage, not shown, or to subsequent steps wherein the stock may be treated with an alkaline sulfide solution, as described in U. S. 1,980,555 to render it stable toward formation of deleterious compounds.

Considering further our invention from the view point of the most efficient utilization of the oxidizing power or oxidation potential of the treating solution, the process sums up to be essentially a two-stage treating process using a single contacting pump. Sour oil entering through line 3 contacts in contactor 6 partially spent treating solution. Following this step, partially sweetened oil then contacts regenerated treating solution in mixer 1. In further explanation, the fully regenerated treating solution entering through line 11 may have an oxidation potential as high as 420 millivolts, upon passing through the centrifugal mixer 1, this potential may be reduced to, say, 390 m. v., this partially spent solution then separates from the sweetened oil in separator 2, and passes by line 13 to line 3 to contactor 6, wherein the oxidation potential may drop to as low as, say, 360 m. v., and in this condition the solution is generally considered fully spent. In contactor 6 the easy-to-sweeten mercaptans have been oxidized by the above said partially spent treating solution of, say, 390 m. v., while those not so sweetened but are slower and more difficult to sweeten are treated by the fully regenerated copper solution of, say, 420 m. v. in the centrifugal contactor 1, thus giving in effect the above said two-stage contacting.

In contrast to this herein disclosed countercurrent two-stage operation, in conventional practice the regenerated copper treating solution of, say, 420 millivolts, contacts the sour oil wherein the high oxidation potential expends itself in sweetening the mercaptans which are easiest to sweeten. The resulting treating solution, partially spent and possessing a much lowered oxidation potential, then must react with the very-slow-to-react mercaptans, and for this reason contacting times are materially increased in certain rather exceptional cases.

In case the oil contains mercaptans which are extremely refractory toward sweetening, the valve 22 in bypass line 21 may be opened to permit bypassing or recycling of an amount of the copper

treating solution and the treated oil. The bypassed oil mixes with the sour oil in line 3 while the bypassed partially spent treating solution mixes in line 3 with the treating solution from line 13. In this manner the theoretical oil retention and therefore contacting time in the system is increased in proportion to the amount of oil bypassed. As stated above, primary mercaptans react rapidly with the cupric chloride solution while the tertiary mercaptans react relatively slowly, and the latter is especially true in case of high molecular weight tertiary mercaptans. In the chemical oxidation reaction between, for example, butyl mercaptan and cupric chloride, di-butyl disulfide is formed, and secondary amyl mercaptan should yield the corresponding diamyl disulfide. In like manner a tertiary mercaptan should yield the corresponding di (tertiary) disulfide, and it is this latter type of mercaptans which is slow to react. In all these said oxidation reactions, two molecules of the mercaptans are involved. Since two molecules are involved, they may be like molecules or unlike molecules, thus we may have formed a butyl-amyl-disulfide, or a hexyl-secondary or tertiary amyl disulfide. These mixed disulfides may be formed in accordance with the law of probabilities, and a mixed disulfide, for example, primary butyl-tertiary amyl disulfide should be formed from its constituents more easily than will di (tertiary) amyl disulfide. It is known in practice that the addition of a small proportion of a primary mercaptan assists in the sweetening of an oil which is very difficult or slow to sweeten, and the above explanation is given in an attempt to explain this known fact. And it is also known that a trace of sourness appearing in the oil discharged from the mixing pump 1 usually disappears upon opening of the bypass valve 22 permitting recycling to occur. Essentially any proportion of the mixing pump discharge may be recycled, as say from 10% to as high as 50-60% by volume. Upon recycling as much as this 50% materially increases the retention time of the oil in the treating system.

Example

Three thousand barrels per day of gasoline generally considered "difficult to sweeten," equivalent to 125 barrels per hour, were treated in a plant of design illustrated in the accompanying drawing. The mixture of gasoline and treating solution passing valve 17 was composed of 60 volume percent of gasoline to 40 volume percent of treating solution. The regenerated copper solution added through line 11 possessed an oxidation potential of 410 millivolts. After thorough contacting in the centrifugal mixing pump 1, the treating solution taken from sampler 14 had dropped to a potential of 390 millivolts, a decrease of 20 m. v. Upon settling out the treating solution in tank 2, the treated gasoline was fully sweet to the standard doctor test. The settled treating solution of 390 millivolts was then passed to the contacting column 6 in which contact was made with the sour charge stock, the potential of the treating solution herein being reduced to 360 millivolts. This fully spent solution was separated from the partially sweetened gasoline in separating tank 8 and sent to a regeneration unit. The size or capacity of separator tank 2 was such that the gasoline therein had a retention or settling time of 5 minutes. Tank 8, having the same volumetric capacity as separator tank 2, and carrying the copper solution level correspondingly as high in tank 8 as it is carried low

in tank 2, gave the copper solution a settling time of 7½ minutes, which was ample to free the copper solution of oil.

The retention time of the treating solution in separating tank 2 was very short, being approximately ½ minute; thus as this solution was withdrawn through line 13 it was not entirely free of sweetened gasoline, having retained therein 2 or 3 volume percent gasoline. It was found that this "carry back" of gasoline was not detrimental to the process in any way, and in fact was equivalent to the recycling of the gasoline-treating solution mixture through line 21, but, of course, to a lesser extent.

Similarly, the very short retention time of the gasoline in tank 8 did not permit complete settling of all the treating solution and 3 or 4 volume percent of the spent treating solution was carried from tank 8 to mixing pump 1 with the partially sweetened gasoline. This carry-over of spent treating solution lowered the oxidation potential of the regenerated treating solution added through line 11 by 2 to 3 millivolts, which drop was considered negligible.

The oxidation potential values given herein are given merely in explanation of the operation of the process, and are not intended to be a limiting factor in any manner. The oxidation potential drop upon contact with the sour oil is dependent upon several factors, for example, the sourness of the oil, the ratio of sour oil to treating solution as well as upon other factors of lesser importance. The extent to which regeneration of the spent treating solution is carried is dependent upon such factors as plant design, sourness of the oil to be sweetened, and the relative ease with which the oil can be sweetened, in general, the more difficult the oil to sweeten the higher the oxidation potential should be carried.

It will be understood that suitable corrosion-resistant materials of construction are used in constructing the apparatus shown in the drawing.

It will also be understood by one skilled in the art that points of design, tank sizes, and many other variable points may be altered within rather wide limits and yet remain within the intended scope and spirit of our invention.

What we claim is:

1. The process of sweetening a sour hydrocarbon oil in which at least a portion of the sourness is slow to sweeten which comprises introducing said sour oil into an extended flowing and treating zone, separately introducing an aqueous copper treating solution to said zone into admixture with said oil, passing said mixture along said zone wherein agitation of the mixture occurs to produce contact between the oil phase and the aqueous phase wherein a portion of the sourness is

sweetened, passing the partially sweetened oil and copper treating solution mixture to a separating zone, separating this mixture into a first lower layer of copper treating solution and an upper layer of partially sweetened oil, and removing the said first lower layer of copper treating solution;

5 10 15 20 25 30 35 40 45 50 55

passing the partially sweetened oil into a second contacting zone, separately introducing further aqueous copper treating solution to said second contacting zone into admixture with the partially sweetened oil, vigorously agitating said admixture to effect sweetening of the sourness slow to sweeten, passing this latter resulting mixture to a second separating zone, separating this mixture into a second lower layer of copper treating solution and an upper layer of sweetened oil, and removing said sweetened oil; recycling said second lower layer of copper treating solution as the first mentioned aqueous copper treating solution.

2. The process of sweetening a sour hydrocarbon oil in which at least a portion of the sourness is slow to sweeten which comprises introducing said sour oil into an extended flowing and treating zone, separately introducing a partially spent aqueous copper treating solution to said zone into admixture with said oil, passing said admixture along said zone wherein agitation of the mixture occurs to produce contact between the oil phase and the aqueous phase wherein a portion of the sourness is sweetened and the partially spent copper treating solution becomes spent, passing the partially sweetened oil and spent copper treating solution mixture to a separating zone, separating this mixture into a lower layer of spent copper treating solution and an upper layer of partially sweetened oil, and removing the said spent copper treating solution; passing the partially sweetened oil into a second contacting zone, separately introducing regenerated copper treating solution to said second contacting zone into admixture with the partially sweetened oil, vigorously agitating said admixture to effect sweetening of the sourness slow to sweeten and wherein the regenerated treating solution becomes partially spent, passing this latter resulting mixture to a second separating zone, separating this mixture into a partially spent copper treating solution layer and a layer of sweetened oil, and removing said sweetened oil; recycling said partially spent copper treating solution as the first mentioned partially spent copper treating solution.

3. Same as claim 2, in which a portion of the latter resulting mixture passed to the second separating zone is bypassed from the said second separating zone into the extended flowing and treating zone.

H. E. MESSMORE.
J. M. MASON.
